CLAIM

The ornamental design for a portion of a crib, as shown and described.

DESCRIPTION

FIG. 1 is a front perspective view of a portion of a crib showing my new design;

FIG. 2 is a front elevational view thereof with the opposite side being a mirror image;

FIG. 3 is a cross section taken along the line 3—3 of FIG. 2; and,

FIG. 4 is a top plan view thereof.

The broken line showing of the remainder of the crib is for illustrative purposes only and forms no part of the claimed design.
